UNITED STATES PATENT OFFICE.

VIRGIL H. BODLE AND FRED C. FRANCISCO, OF AKRON, OHIO, ASSIGNORS TO THE
B. F. GOODRICH COMPANY, OF NEW YORK, N. Y., A CORPORATION OF NEW YORK

LASTING MACHINE.

Application filed July 1, 1925. Serial No. 40,782.

This invention relates to machines for lasting shoes, in the broad sense of applying shoe parts to lasts, and is especially applicable to the lasting of shoes comprising rubberized or 5 rubber parts, although not wholly limited thereto.

Our general object is to provide an improved lasting machine of simplified and dependable construction. Further objects are 10 to provide a machine readily adaptable for accurate operation upon either right or left shoes, and to reduce the number of parts necessary for the actuation of certain types of work-manipulating mechanisms as compared 15 with machines heretofore known. Other, more detailed, objects will become manifest as the description proceeds.

Of the accompanying drawings:

Figure 1 is a side elevation of the preferred 20 embodiment of our invention.

Figure 2 is an end elevation of the same, from the left of Figure 1.

Figure 3 is a section on line 3—3 of Figure 5.

25 Figure 4 is a section on line 4—4 of Figure 2 and Figure 6.

Figure 5 is a section on line 5—5 of Figure 1.

30 Figure 6 is a section on line 6—6 of Figure 4.

Figure 7 is a vertical section of a portion 35 of the machine showing in elevation one of a set of upper-manipulating or gripper units in upper-receiving position.

Figures 8, 9, 10, 11 and 12 are similar views 40 showing later successive stages of operation.

Figure 13 is a perspective view of one of the units.

Figure 14 is a fragmentary vertical section 45 through the same.

Figure 15 is a section on line 15—15 of Figure 14.

Figure 16 is a section on line 16—16 of Figure 44.

General description.

The machine comprises a bearing standard 10 formed with various bearings, guides and brackets for the moving parts and supporting an annular, fixed, supporting frame 11 for a set of upstanding gripper units surrounding the lasting position. The annular frame 11 is adapted to permit vertical reciprocation of a last-support 13 to carry 55 a bare last from lasting position, where the

last is received, to a lower position, out of the way of the gripper units, and then to return the last to lasting position to force it into an upper meanwhile mounted in the gripper units. The gripper units are adapted collectively to receive the sole margin of the upper between their gripper jaws and to position it therein by the retractive movement of yieldingly closed positioning jaws which lightly draw the margin into the gripper jaws and slide upon the margin in further movement after the margin has been stopped at a determinate position in the gripper-jaws. The said gripper units are adapted to anchor the upper's margin, as thus 70 positioned, while the last is forced into the upper, and then to fold inward the upper's margin and stick it onto the sole face of the last, or an insole thereon.

Two annular actuating frames 14 and 15, 75 surrounding the lasting position, are adapted concurrently to actuate the gripper units throughout the machine's entire cycle of operations, and suitable drive mechanism is provided for moving the last-support and the 80 two actuating frames in determinate time relation throughout two successive movements constituting the cycle, automatically stopping at the end of each movement.

The gripper units are pivotally mounted 85 upon the fixed frame 11, to tilt from and toward the last in the lasting operation, and adjusting means is provided for concurrently tilting certain of the gripper units at opposite sides of the last, by modifying their 90 connection to the actuating frame 15, so as to change the configuration defined by their gripper jaws and thus to adapt the machine to operate upon right or left shoes alternatively.

Gripper units.

Each of the gripper units comprises an L-shaped jaw-carrier 16 having an upstanding, jaw-carrying arm 16^a and an outwardly projecting, approximately horizontal, acutating arm 16^b, the jaw carrier being provided at its elbow with opposite pivot studs 17, 17 mounted in respective vertical slots 18, 18 formed in the forks of a bifurcated post 19 straddling the jaw carrier and secured in an aperture in the fixed frame 11 by a set screw 20. The upper end of each slot 18 is closed by a cross-pin 21 to limit upward movement of the jaw carrier.

The vertical arm 16^a of the jaw carrier 16 comprises a pair of side plates 16^c, 16^c spaced apart by a plate 16^d (see Figs. 13, 14) and formed at their upper ends with aligned, 5 oblique, twin gripper jaws 22, 22 adapted to mate with twin gripper jaws, 23, 23 formed respectively on the upper ends of a pair of slide bars 24, 24 which embrace the spacer plate 16^d, are slidably mounted in guide ways 10 formed in the side plates 16^c and are joined at their lower ends, below the spacer plate 16^d, by a pin 25 which projects at each side of the pair of slide bars, its respective end portions being mounted in slots formed in 15 the respective forks of a bifurcated lever 26 which is pivoted at 27 upon a bracket 28 secured to the side plates 16^c, the said lever 26 being adapted to open and close the gripper jaws 23 with relation to their mates 22.

20 The lever 26 is constantly urged toward jaw-opening position by a compression spring 29 interposed between its outer arm and the horizontal arm 16^b of the jaw carrier. For turning it toward jaw closing position, 25 against the force of said spring, its outer arm is formed with an oblique cam face 30 adapted to be abutted by a cam shoulder formed on a C-shaped lever 31 which has a bifurcated end straddling the pair of side 30 plates 16^c and pivoted thereto at 32.

Pivoted on the other end of the lever 31 at 33 is the lower jaw member 34 of a pair of sliding, upper-position jaws adapted to draw the margin of the upper into the gripper 35 jaws 22, 23, the upper jaw member 35 of said pair being hinged to the lower jaw 34 at 36. The jaws 34, 35 are slidably mounted between the twin gripper jaws 22 and between the twin gripper jaws 23, and the 40 lower sliding jaw 34 is adapted to be supported by and to run upon a roller 37 journalled between the side plates 16^c upon a pin 38 mounted in said side plates and having pivoted upon its end portions the respective 45 ears of a double plate lever 39 which is formed with an upstanding guide finger 40 for guiding the margin of the shoe upper into the jaw assembly. The side plates of said finger are formed with respective aligned notches 50 41 adapted to admit the margin into the jaws 22, 23, the walls of said notches, at their angles, serving as abutments for the upper's margin, to stop the latter as it is drawn into the jaws 22, 23 by the sliding jaws 34, 35, 55 and so to position the margin accurately in the gripper jaws prior to the closing of the latter.

Turning movement of the lever 39 about its pivot 38 toward the lasting position is 60 limited by shoulders 42, 42 formed on the adjacent faces of the plates of the guide finger 40 and adapted to abut the upper end faces of the respective side plates 16^c of the jaw carrier. For yieldingly urging the lever 39 65 toward that stopped position and for open-

ing and closing the sliding jaws 34, 35 and urging them toward their projected, open position, an L-shaped double plate dog 43 has its plates at one end pivoted at 43^a to the respective plates of the lever 39 and its plates 70 at its other end connected by a pull spring 44 with a middle part of the C-shaped lever 31, the plates of said dog lying between the plates of the lever 39 and embracing the sliding jaws 34, 35 and having journalled between them at their elbow a roller 45 adapted to run upon the upper face of the sliding jaw 35, yieldingly to urge the jaw 35 toward closed position, under force of the spring 44, 75 throughout the greater part of the range 80 of sliding movement of the jaws 34, 35, and adapted to engage a projection 46 upon the hub of the jaw 35 and thereby to open said jaw as the sliding jaws arrive at the limit of their projective movement.

For turning the C-shaped lever 31 about its pivot 32, against the force of the spring 44, to retract the sliding jaws 34, 35 and to cause them to close lightly upon the upper and draw its margin into the gripper jaws, a 90 roller 47 adapted to bear upon the upper edge face of the lever 31 is journalled upon a bar 48 pivoted at 49 upon a bracket 50 secured to the actuating frame 14, said bar being yieldingly held upward against an 95 adjusting screw 51 mounted in said frame by a C-shaped hinge-spring 52 connecting the bar with its bracket. The C-shaped lever 31 is formed with an arcuate margin 53 for coaction with the roller 47, the lever 31 being so formed that, when it is at the limit of its jaw closing movement, the said arcuate margin will be concentric with the pivot 17 of the jaw carrier 16, so that the 100 gripper assembly may be tilted toward the lasting position while the roller 47, running upon the arcuate face 53 of the lever, continues to hold the gripper jaws closed and the sliding, upper-positioning jaws retracted 105

For yieldingly urging each jaw-carrier 16 110 to tilt toward the last, the outer end of its horizontal arm 16^b, as to the gripper units about the heel and toe of the last, which do not require special adjustment for right and left shoes, has hinged thereto at 54 a downwardly extending spring rod 55 projecting loosely through an aperture 56 in the actuating frame 15, as shown clearly in Fig. 7, and a compression spring 57 is mounted upon said rod between a shoulder 58 formed thereon and the actuating frame 15. For positively 115 tilting the jaw-carrier outward, a pull rod 59 is hinged to the jaw carrier's horizontal arm 16^b at 60 (Fig. 7), extends downwardly through an adjustable bushing 61 screwed into the actuating frame 15, and has a retaining nut 62 on its lower end, below the bushing and abutting the latter under the force of the spring 57, the bushing 61 being adapted to be 120 screwed upward or downward to lengthen or 125 130

shorten this positive link connection of the actuating frame 15 with the jaw-carrier arm 16^b.

In order that the similar connections of the 5 jaw-carrier arms 16^b along each side of the last may be quickly and concurrently adjusted to adapt the machine for right or left shoes, the spring rods 55 of each of these jaw-carriers extend through a countersunk aperture in a block 63 overlying the actuating frame 15 (Figs. 4 and 6) and secured to the tops of a pair of vertical guide stems 64, 64 slidably mounted in apertures in the frame 15, there being one of these blocks 63 at each side 10 of the last, and the compression spring 57 on the rod 55 seats in the countersink of the block. The pull rod 59^a of each of these gripper units extends loosely through a sleeve 65 which is adjustably secured in the block 63 by 15 a set screw 66, and slidably extends downward through an aperture in the frame 15. The pull rod 59^a has its upper end screwed into a clevis member 67 hinged to the jaw carrier arm 16^b at 68, and the lower end of the 20 pull rod is formed with a knurled head 69 held against the lower end of the sleeve 65 by 25 the force of the spring 57.

For raising the block 63 at one side of the machine and concurrently lowering the block 30 63 at the other side of the machine, to tilt one group of jaw carriers toward the last and the other away from the last for right and left adjustment, while the frame 15 remains stationary, each of the guide stems 64 of the 35 blocks 63 is slotted at its lower end, the slot being traversed by a cross pin 70 mounted in an oblique slot 71 formed in a cam plate 72 projecting downward from a transverse arm 73 mounted for sliding movement in a suitable dove-tail guide 73^a (Fig. 1) formed in the lower face of the actuating frame 15, the 40 several arms 73 being secured to an annular frame 74 connected by a link 75 (Fig. 6) with a bell crank 76 having a handle 77 (Fig. 1) for sliding the annular frame 74 and its arms 73 transversely of the machine and thus cause the cam plates 72 to raise one pair of the 45 blocks 63 while lowering the other. Respective latching devices 78, 78, (Fig. 1) are 50 mounted on the under face of the frame 15 and are adapted to engage the bell crank 76 to hold the parts in one or the other of the positions of right and left adjustment.

55 Last manipulating-mechanism.

The last support 13 is formed on its upper face to fit an insole 79 mounted under the last 80 (Fig. 7), and is mounted upon the top of a post or standard 81 which is supported by 85 and secured to a cross head 82 slidably mounted upon a pair of guides 83, 83 formed upon the bearing standard 10 (Figs. 1, 4, 5 and 6). For raising and lowering the cross head 82, said cross head has hinged thereto 90 at 84 a connecting rod 85 which extends down-

ward through a block 86 (Fig. 1) with a sliding fit, said connecting rod being provided with a pair of nuts 87, 88 bearing respectively upon the under face of the block and upon the upper end of a compression spring 89 interposed between the upper nut 88 and the block, for adjusting its effective length. The block 86 is formed with opposite trunnions 90, 90 mounted in the ends of the parallel 70 arms 91, 91 of a double lever (Fig. 1) which has a cam roller 92 (Fig. 2) journaled between its arms at an intermediate part thereof and adapted to run upon the periphery of a cam disk 93 (Figs. 1 and 2) secured upon a shaft 94 which is journaled in bearing 75 brackets 94^a, 132 and 138, the rear end of the lever 91 being pivoted at 95 (Fig. 2) in the top of suitable brackets 96, 96 rising from the base of the standard 10.

The upper face of the last support 13 is so 80 formed as to give the last a forward tilt, as will be clear upon reference to Fig. 8, so that the reinforced portion of the upper at the heel of the last will be pulled to a comparatively close-in position and will not require 85 excessive contracting or fulling of this relatively thick and stiff portion of the upper in applying its margin to the insole, the gripper units being so positioned and proportioned 90 as to pull the upper's margin to appropriate 95 positions corresponding to the tilt of the last, as will be apparent upon reference to Fig. 1.

Such tilting of the last also results in the pulling of the upper at the toe of the last to a comparatively out-standing position, so that 100 the fabric is not pulled too abruptly downward over the point of the toe of the last and consequently does not bind excessively by friction against the last at that position.

The inclined position of the set of gripper 105 units and the last, with relation to their direction of relative movement, which movement of the last is non-perpendicular to the sole face of the last, the last moving with its heel portion somewhat in advance of its toe portion, 110 thus improves the operation at both the toe and the heel of the last.

Drives for actuating frames.

The higher actuating frame 14 is supported 115 upon two pairs of slide bars 97, 97 which extend slidably through the lower actuating frame 15 and through guide brackets 98, 99 formed on the standard 10, the lower ends of the bars of each pair being connected by a 120 head 100 which is connected by a link 101 with a lever 102 secured to a rock shaft 103 journaled in the brackets 132, 138. For rocking the shaft 103 a rocker arm 104 (Figs. 1, 2 and 5) is secured thereto and is provided at 125 its outer end with a cam roller 105 mounted in a cam groove 106 formed in the side face of a cam disk 107 secured upon the shaft 94.

The lower actuating frame 15 is supported 130 and adapted to be raised and lowered by two

- pairs of vertical slide bars 108, 108 slidably mounted in suitable apertures in the brackets 98 and 99 and the bars of each pair are connected at a position between the said brackets 5 by a cross member 109 retained in place by collars 110, 110 secured upon the bars. Each of the said cross members is formed at its forward end with a gear segment 111 with which is meshed a pinion 112 secured upon a hollow 10 shaft 113 (Fig. 5) rotatably mounted in the outer ends of arms 114, 114 which are pivoted as at 115 (Fig. 2) to the respective cross members 109, the pivot 115 being concentric with the gear segment 111, so that the pinion 112 15 may run upon the gear segment in mesh therewith.

Extending through the hollow shaft 113 and through arms 116, 116 pivoted to the respective cross members 109 at the axis 115 is a clamping rod 117 provided with a hand wheel 118 threaded upon one end thereof, for clamping the arms 116 against the pinions 112 and the ends of the hollow shaft 113 to prevent rotation of the pinions and thus to secure the latter in adjusted positions upon the gear segments 111. A hand wheel 119 is secured upon the hollow shaft 113 for running the pinions 112 upon the gear segments, to adjust the arms 114, 116 with relation to the cross members 109. A scale 119^a is secured upon the hollow shaft 113 and is associated with an indicator 119^b secured upon one of the arms 114 (Figs. 1 and 5) for indicating the adjustment.

- 35 Links 120, 120 are pivoted to the respective arms 114, 116 as at 121, Figure 2, and as at 122 are pivoted to respective arms 123, 123 secured to a rock shaft 124 journaled in the standard 10 and provided with a rocker arm 40 125 which has at its outer, lower end, a cam roller 126 mounted in a cam groove 127 formed in the side face of a cam disk 128 secured upon the shaft 94.

45 For driving the shaft 94 and thereby raising and lowering the last-support 13 and the actuating frames 14 and 15 in timed relation the said shaft 94 has secured thereon a gear 129 meshed with a pinion 130 secured upon a hollow spindle 131 which is journaled in the bearing bracket 132 (Figs. 3 and 5) and is formed integrally with a brake drum 133 and a jaw-clutch member 134, said jaw clutch member being adapted to mate with a jaw-clutch member 135 slidably keyed upon a 50 shaft 136 which is journaled in the brackets 96, 96, 138 rising from the base of the standard 10, the shaft 136 rotatably extending into an anti-friction bushing 139 (Fig. 3) mounted in the hollow spindle 131, and said shaft 136 being provided with a drive pulley 55 136^a and a drive belt 136^b thereon.

For engaging and disengaging the jaw-clutch member 135 with its mate 134 the member 135 is provided with a shipper lever 140 secured upon a shaft 141 (Figs. 2 and 3).

The said shaft has secured thereto a downwardly extending rocker-arm 142 constantly urged toward de-clutching position by a pull spring 143 connecting it with the base of the machine, and a link 144 connects said rocker arm with an arm 145 secured to a rock shaft 146 running to the front of the machine and there provided with a treadle 147, adapted for engaging the clutch against the force of the spring 143. 70 75

For latching the clutch in engagement a latch arm 148 (Fig. 3) is secured to the rock shaft 141 and is adapted to latch upon a shoulder 149 formed upon an upstanding arm 150 of a two armed lever pivoted upon a stud 151 projecting from the machine frame. The lower arm 152 of the said lever is connected by a pull rod 153 with a treadle 154 (Figs. 1 and 5) at the front of the machine for unlatching the arm 150 from the arm 148 to stop the machine in emergency. To prevent overrunning of the machine a brake arm 155 is secured to the rock shaft 141 and provided at its outer end with a brake-shoe 156 adapted to coact with the brake drum 133 under the force of the spring 143, whenever the latter is permitted to disengage the clutch. 80 35 90

For automatically stopping the machine at the end of each of the two movements of the cycle, the cam disk 128 is provided on its side face with dogs 157, 158 adapted to engage a tripper arm 159 extending from the hub of the latching arm 150 and connected with the base of the machine by a pull spring 160 adapted to urge the arm 150 toward latching position. 95 100

Operation.

The machine is shown in Figs. 1, 2, 5 and 6 with parts in the positions which they occupy as the machine is stopped at the end of the complete cycle of operations, the dog 157 being in contact with the tripper arm 159 to unlatch the clutch and stop the machine. It will be observed that when the machine stops, the cam roller 92 (Fig. 2) is upon the second highest reach A of its cam 93 and that consequently the last-support is at approximately the elevated position of Fig. 6. The cam roller 105 is in the short-radius portion B of its cam groove 106 and consequently the actuating frame 14 is at its lowermost position, holding the sliding jaws 34, 35 closed and retracted. The cam roller 126 is still within the short-radius reach C of its cam groove 127, so that the actuating frame 15 is in almost its lowest position, with the jaw-carriers still tilted sufficiently away from the last-support to permit the mounting of a last thereon. 105 110 115 120

With the parts in these positions an insole 79 and a last 80 are placed upon the last support 13 as shown in Fig. 6. The machine being thrown in gear by the pressing of the treadle 147 the arm 148 latches upon the arm 150 and the shaft 94 is driven clockwise as 130

viewed in Fig. 2 until the dog 158 strikes the tripper arm 159 and thereby brings the machine to a stop.

- During this movement the last support 5 with the last and insole thereon are lowered to the position of Fig. 7 the cam roller 92 passing onto the short-radius reach D of its cam 93. At the same time the actuating frame 14 is raised the cam roller 105 passing 10 into the long-radius reach E of its cam groove 106, and as the machine is brought to a stop by the dog 158 the sliding jaws 34, 35 are held projected as in Fig. 7 by the spring 44 and the upper sliding jaw 35 is held open, as 15 there shown, by the roller 45 in engagement with the projection 46 on the hub of said jaw, the spring 44 also holding the guide finger 40 in stopped position against the upper end faces of the gripper jaws 22.
- 20 In this movement the lower actuating frame 15 is slightly raised, the cam roller 126 (Fig. 2) passing into the reach F of its cam groove, this slight upward movement of the frame 15 permitting the jaw-carriers to tilt 25 slightly toward lasting position for reception of a conoidal upper 163 to be presented thereto as shown in Fig. 7. At this time, with the machine stopped by the dog 158, the studs 17 are in the lower ends of their slots 18, as 30 shown in Fig. 7, the pull rod 59 being under tension and the horizontal arm 16^b of each jaw-carrier being urged about the pivot 60 by the compression spring 57. At this time also the lower gripper jaw 23 is held open by 35 the spring 29, the C-shaped lever 31 being held out of contact with the lever 30 by the pull spring 44, as shown in Fig. 7.

With the gripper units at the heel and toe of the last thus held in the position of Fig. 40 7, and the gripper units at the sides of the last being held in similar positions, the upper 163 is placed upon the set of lower sliding jaws 34 as shown in Fig. 7, and the machine is again started, by depressing the treadle 147, 45 and continues to be driven until the dog 157 again strikes the tripper lever 159 to stop the machine.

At the beginning of this second movement of the cycle the lower actuating frame 15 is 50 slightly raised by the cam roller 126 passing up the short incline G of its cam groove, to tilt the jaw carriers slightly further toward the lasting position so as to cause the walls of the notches 41 to define a figure having substantially the same perimeter as the heel 55 margin of the upper, the gripper units then being held to this configuration while the cam roller 126 is on the reach H of its cam groove.

Immediately after this short inward tilting 60 of the gripper units, the actuating frame 14 is lowered, the cam roller 105 passing down the incline I of its groove, and this lowering of the frame 14 causes the rollers 47 to bear 65 upon the arcuate edge faces 53 of the C-shaped levers 31, turning the latter about

their pivots 32, against the force of the pull springs 44 and thereby causing the sliding jaws 34, 35 to be retracted past the gripper jaws 22, 23, the upper sliding jaw 35 being lightly closed by the cam roller 45 at the beginning of their retractive movement and being held lightly closed by the said cam roller as the sliding jaws continue to be retracted, so that the sliding jaws draw the margin of the upper into the gripper jaws 22, 23 until the edged face of the margin abuts the walls of the notches 41 in the fingers 40 and is positioned thereby, as shown in Fig. 8, the sliding jaws 34, 35 then slipping upon the fabric margin of the upper throughout the 80 rest of their retractive movement, to the position of Fig. 9.

Near the end of this retractive movement of the jaws 34, 35, the C-shaped lever 31 contacts the lever 30 as shown in Fig. 9, and turns the latter about its pivot 27, against the force of the spring 29, to force upward the slide bars 24 and thereby close the lower gripper jaws 23 upon the fabric, against the jaws 22.

Meanwhile the last support 13 is elevated 90 by the cam roller 92 passing up the incline J of its cam 93, and shortly after the gripper jaws are firmly closed upon the upper's margin the last arrives at its uppermost position and is forced into the upper while the latter is 95 held by the grippers.

As soon as the last has thus been forced fully into the upper and while it remains in that position, the cam roller 92 running on the concentric portion K of its cam 93, the lower actuating frame 15 is further raised by the cam roller 126 passing into the long-radius portion L of its groove, whereby the gripper units are tilted toward the last until they carry the margin of the upper against the last support 100 13, as shown in Fig. 10, the guide-fingers 40 pressing the upper against the corner of the last, as there shown, but yielding to permit the gripper jaws to carry the margin under the last, the said gripper jaws being held 105 closed and the sliding jaws being held retracted during the inward tilting of the jaw carriers by the rollers 47 running upon the arcuate margins of the levers 31.

The actuating frame 14 is then raised by 115 the cam roller 105 passing into the long-radius reach M of its groove, which first permits the springs 57 to raise the jaw-carriers to carry the upper's margin against the insole 79 and stick it thereto, as shown in Fig. 11, the upper being cemented along its margin as 120 shown at 164, (Figs. 7, 8 and 9), and the jaw-carrier's pivot studs 17 sliding vertically in their slots 18. As the gripper jaws thus carry the upper's margin against the insole they 125 are guided by the face of the last support 13, so that they apply the margin with a determinate amount of over-lap upon the insole.

Further upward movement of the frame 14 permits the pull springs 44 to raise the C- 130

shaped levers 31 from the respective jaw-closing levers 26, thus permitting the springs 29 to open the gripper jaws and release the unattached portion of the upper's margin therefrom, and projecting the sliding jaws 34, 35. During the first part of the projective movement of the said sliding jaws the upper jaw 35 slides inwardly upon the unattached portion of the upper's margin previously held by the gripper jaws and progressively sticks it to the insole, the work being held down by hand, and the jaws 34, 35 together, sliding over the edge of the last support 13; lift the last therefrom. As the sliding jaws approach the limit of their projective movement the rollers 45 by contact with the upper jaws' hub projections 46 cause the jaws 35 to lift from the jaws 34 and collectively to support the work approximately as shown in Fig. 12, the gripper units meanwhile being tilted far outward and returned to their lowermost positions in the slots 18 by the cam roller 126 passing down the incline N of its groove and causing the jaws 35 to slide outward in pressing relation to the margin of the upper, so that the upper is ironed out toward the edge of the insole from its cemented zone, after which the frame 14 is lowered, as its cam roller 105 passes again into the short-radius reach B of its groove, and the sliding jaws 34, 35 are thereby gradually retracted and closed. During this movement, at about the position of Fig. 12, the work is simply lifted from the machine by hand and passed on to the next operation. At the end of this movement, which is stopped by the dog 157 striking the tripper arm 159, the gripper units have returned to the starting position of Figure 6. Near the end of the movement the last support 13 is slightly lowered, by the cam roller 92 passing from the long-radius portion K of its cam onto the portion A of slightly shorter radius, so that the support is slightly lowered to a position such that the jaw-carriers may serve as gages for the purpose of positioning the next insole and last. The operation as described is then repeated.

Adjustment of the machine to change from right to left shoes or vice versa is readily effected by simply turning the bell-crank handle 77 from one of the latching devices 78 to the other, as will be readily understood upon reference to the above description of the adjusting devices.

The employment of means such as the levers 26, actuated by the jaw-retracting levers 31, for closing the gripper jaws, eliminates the need of one of the three actuating frames heretofore employed in machines of generally similar character, and permits the use of simple mechanism for right-and-left adjustment. The reduction in the number of actuating frames also permits the simplification of driving means.

The division of the cycle of operations into

two successive movements, with the last-support starting the cycle from its uppermost position, permits a single operator conveniently to mount both the last and the upper in the machine and permits a great reduction in the height of the machine as compared with prior constructions in which the last-support required to be lowered clear of the actuating frames for the introduction of the last thereto, below the frames, from the side of the machine. Other and more detailed advantages will be manifest.

Our invention is susceptible of modification within its scope, and we do not wholly limit our claims to the specific construction shown.

We claim:

1. A lasting machine comprising a set of jaw carriers defining a lasting position, a pair of gripper jaws mounted on each of said carriers, stock-positioning means mounted on each of said carriers for drawing a piece of stock into the gripper jaws thereon, a jaw-closing member movably mounted upon each of said carriers and adapted in one part of its range of movement to actuate said stock-positioning means and by further movement to close the gripper jaws, means movable with relation to said jaw carriers for concurrently actuating said jaw-closing members, the latter being adapted to be similarly actuated by said actuating means notwithstanding their different positions of adjustment from or toward the lasting position, and means for concurrently adjusting some of said jaw carriers toward and others away from the lasting position to adapt them for right or left shoes alternatively.

2. A lasting machine comprising a set of stock-anchoring units defining a last position and pivoted to tilt from and toward a last held in said position, each comprising means for anchoring the margin of a piece of stock and an actuating member for said anchoring means so formed with an arcuate face that said face will be substantially concentric with the pivot of the unit when in anchoring position, means adapted to bear upon the arcuate faces of the said actuating members concurrently to actuate said anchoring means and maintain them in their anchoring condition while the units are tilted toward the last, means for concurrently tilting said units, and means for concurrently modifying the connections of the last said means to certain of the units so as to adapt them for right or left shoes alternatively.

3. A lasting machine comprising a set of stock-anchoring units defining a last position and each comprising means for drawing the margin of a piece of stock to a determinate position and there anchoring it, and means for concurrently shifting the positions of certain of said stock-anchoring units to adapt them for right or left shoes alternatively.

4. A lasting machine as defined in claim 3

in which each stock-anchoring unit is pivoted to tilt from and toward the lasting position and the shifting means is adapted to function by tilting the units.

- 5 5. A lasting machine comprising a set of stock anchoring units defining a lasting position and pivoted on axes approximately parallel to the adjacent part of the sole edge of the last to tilt toward a last held in said position to carry the margin of an upper inward about the sole margin of the last, actuating means for concurrently so tilting said units, and means for concurrently modifying the connections of said actuating means to certain of said units so as to give them initial angular positions with relation to their pivots such as to adapt them for right or left shoes alternatively, the tilting means comprising an actuating frame structure common to the units and link connections from said frame structure to the units, certain of said link-connections comprising cam means for varying their effective lengths. 6. A lasting machine comprising a set of L-shaped jaw carriers defining a lasting position and pivoted at their elbows to tilt from and toward a last held in said position, the several carriers comprising jaw-carrying arms extending in the same general direction toward the last and actuating arms extending outward from the set, an actuating frame structure common to the units, for tilting them from and toward the last, link connections from said frame structure to the several units, certain of said connections comprising cam means for varying their effective lengths, and interconnected means for concurrently actuating the said cam means oppositely at different parts of the set to adjust the machine for right or left shoes alternatively. 7. A lasting machine comprising a set of jaw carriers, a pair of gripper jaws mounted on each carrier, stock-positioning means mounted on each carrier and having a projective and retractive movement for receiving the sole margin of an upper and drawing it into the gripper jaws, contact actuating means comprising a single contact member for each jaw carrier adapted to actuate the stock-positioning means and then to close the gripper jaws in a single movement, the set of gripper jaws being unobstructed for the free reception of an upper from an axial direction with relation to the set, a movably mounted support adapted to receive a last at the lasting position, withdraw it soleward therefrom and then to return it to the lasting position to force it into an upper held by the jaws, means for moving the gripper jaws to apply the sole margin of the upper to the last, and means for actuating the gripper units and the last support in successive cycles of two movements each, said means being adapted automatically to stop the machine at the end of the first movement with the last- support withdrawn from lasting position and the gripper jaws open, and at the end of the second movement with the last-support in lasting position and the stock-positioning means and the gripper jaws so withdrawn from the lasting position as to permit the free reception of a last by the last-support. 8. A lasting machine comprising a set of stock-anchoring units adapted concurrently to receive and anchor the sole margin of a shoe upper, a last-support for carrying a last into an upper so held, means for actuating said units to carry the upper's margin inward about the sole-edge of the last, and means for so actuating the several elements in successive cycles comprising two movements each that at the end of one movement the last support is adjacent the lasting position and the stock-anchoring units are cleared away for the reception of a last by the last-support and at the end of another movement the stock-anchoring units are in position for the reception of an upper and the last-support is withdrawn from lasting position. 9. A lasting machine comprising last manipulating means, upper manipulating means, and means for so actuating the two said means concurrently in cycles comprising two movements each that at the end of one movement the last-manipulating means is positioned to receive a last approximately at lasting position and at the end of another movement the upper manipulating means is positioned to receive an upper approximately at lasting position and the last manipulating means is withdrawn therefrom, the last-manipulating means and the upper-manipulating means being adapted in one part of the cycle to coact to pull the upper onto the last. 10. A lasting machine as defined in claim 9 in which the upper-manipulating means comprises a set of gripper jaws adapted to move inward past the sole edge of the last during the cycle of operations. 11. A lasting machine comprising a set of jaw carriers surrounding a lasting position, a pair of gripper jaws mounted on each carrier, a pair of upper-positioning jaws mounted on each carrier for projective and retractive movement past said gripper jaws for drawing the margin of an upper thereinto, a last-support adapted to carry a last into an upper held by said gripper jaws, a jaw-actuating member movably mounted on each carrier and adapted in one part of its range of movement to close and retract the upper-positioning jaws and by further movement to close said gripper jaws, and means for so actuating the several said elements as to present the last support for the reception of a last approximately at lasting position while holding the upper-positioning jaws retracted and the carrier assemblies clear of the lasting position, then to withdraw the last support and open the gripper jaws and upper-positioning jaws

for the reception of the upper, then to actuate the said jaws to anchor the upper and to return the last support to force the last into the upper, and then to actuate the carriers to pull 5 the upper inward about the sole of the last.

12. A lasting machine comprising a last-support and co-operatively associated therewith a jaw carrier, a pair of gripper jaws mounted thereon, stock-positioning means 10 mounted on said carrier and having projective and retractive movements for receiving a piece of stock and drawing it into said gripper jaws; and a member movably mounted on said jaw carrier and adapted in one part of its 15 range of movement to actuate said stock-positioning means and by further movement to close said gripper jaws.

13. A lasting machine comprising a last-support and co-operatively associated therewith a jaw carrier, a gripper jaw fixedly mounted thereon, a mate for said gripper jaw 20 movably mounted on said carrier, a pair of

stock-positioning jaws mounted on said carrier for projective and retractive movement past the said gripper jaws, a lever pivoted on said carrier and having pivotal connection to said stock-positioning jaws for imparting to them their projective and retractive movement, and means adapted by contact of said lever to close the said gripper jaws near the 25 end of its retractive movement. 30

14. A lasting machine comprising a last-support and co-operatively associated therewith a jaw-support, a pair of gripper jaws mounted thereon, a pair of stock-positioning jaws mounted thereon for projective and retractive movement past said gripper jaws, and means mounted on said jaw support and common to the two pairs of jaws for actuating 35 the same. 40

In witness whereof we have hereunto set our hands this 24th day of June, 1925.
